UNITED STATES PATENT OFFICE.

DONALD A. ROSE, OF BERKELEY, CALIFORNIA.

FIXTURE DEVICE.

Application filed March 4, 1922. Serial No. 541,107.

To all whom it may concern:

Be it known that I, DONALD A. ROSE, a citizen of the United States, residing at Berkeley, in the county of Alameda and 5 State of California, have invented new and useful Improvements in Fixture Devices, of which the following is a specification.

This invention relates to improvements in chandelier attaching devices.

10 The principal object of this invention is to provide a simple means for attaching a chandelier to an ordinary outlet as commonly employed in electric wiring.

Another object of this invention is to produce a device which may be applied to installations now installed without involving a considerable outlay.

20 A further object of this invention is to produce a device of the character described wherein the electric light fixture may be easily removed as for replacement or for re-wiring.

25 A further object of this invention is to produce a device wherein the wires projecting from the outlet will be securely attached as to binding posts, thereby eliminating the possibility of a short circuit, as is common with outlets where the wires are allowed to dangle after the fixture is removed.

30 Other objects and advantages will be apparent during the course of the following description.

In the accompanying drawings forming a part of this specification and in which like numerals are employed to designate like parts throughout the same,

Fig. 1 is a cross section taken on the line 1—1 of Figure 2,

Fig. 2 is a top plan view of an outlet with 40 part of my device applied thereto,

Fig. 3 is a top plan view of my complete device,

Fig. 4 is a detail cross sectional view taken on the line 4—4 of Figure 2,

Fig. 5 is an enlarged detail cross-section showing the contacts,

Fig. 6 is a perspective detail view of one of the contacts, and

Fig. 7 is a perspective view of the contact 50 carried upon the outer portion of my device.

In the wiring of a building, it is usual to place a metal outlet box upon the wall at a point where the fixture is to be attached. The electric wires leading to the outlet box 55 are either led thereinto through a metal conduit through the center or through open-

ings provided at other points. It is to this outlet box that I propose to attach my invention, thereby forming a means for attaching the free ends of the wires entering there- 60 in, which are now commonly left free.

In the accompanying drawings wherein for the purpose of illustration is shown a preferred embodiment of my invention, the numeral 5 designates a portion of the wall 65 which may be either side wall or a ceiling, while the numeral 6 designates the usual metallic outlet box. This outlet box is provided with openings 7 and 8, through which the wires enter. It is understood, however, 70 that these wires might enter through the opening 9, the result being the same.

At 11 I have shown a block of a contour corresponding with that of the outlet box. This block is preferably formed of insulating material. Openings 12, 13 and 14 are formed in this block and are adapted to register with the openings 7, 8 and 9, while lugs 16 and 17 are secured to the outlet box 6 at points diametrically opposite each other, 80 and are each provided with set screws, as shown at 18 and 19. These set screws are adapted to enter openings 20, as is best shown in Figure 4 formed in ledges 21 recessed in the sides of the member 11. The member 11 is entirely cut away at 22 and 23, 85 so that it may be removed when the set screws 18 and 19 are withdrawn from the openings 20.

Contacts 24 and 25 are secured to the 90 member 11 as by screws 26 and 27.

Binding posts 28 and 29 are secured in each of the contacts and serve as a means for attaching electric wires entering the outlet box. At 31 I have shown a cap, which is 95 adapted to contact the wall 5 and to entirely cover the outlet box 6. This cap is provided with a metallic bushing 32, which is threaded for the reception of the ordinary fixture. This bushing is retained in the cap as by 100 screws 33 and 34.

Contacts are provided upon the cap 31 the same being two in number, and are of the construction best shown in Figure 5, wherein the numeral 36 represents a contact bent 105 upon itself and retained in the cap 36 as by a screw 37.

Each one of these contacts carries a binding post 38, to which the electric wire entering the fixture is attached.

In use, my device operates as follows:—

Member 11 is inserted in the outlet box by

- passing the lugs 16 and 17 through the cut-away portions 22 and 23. The block is then rotated until the screws 18 and 19 are above the openings 20. The set screws are now turned so as to enter the openings 20, which holds the member 11, securely in place and the free ends of the electric wires entering the outlet are secured to the binding posts 28 and 29. The electric fixture is now secured 10 in the bushing 32 and the free ends of the wires extending therefrom are secured to the binding posts 38 carried upon the contacts 36. The fixture, with the cap attached thereto, is next placed against the outlet box and screws, such as shown in dotted line at 30, are passed through the cap 31 and into the member 11, which, as before mentioned, is made of an insulating material, preferably porcelain.
- 20 The assembly is such that the contacts 36 will contact with the contacts 24 and 25, the result being that current will be established from the source through my device and into the fixture.
- 25 It is to be understood that the form of my

invention herewith shown and described is to be taken as a preferred example of the same, and that various changes in the shape, size and arrangement of parts may be resorted to without departing from the spirit of 30 the invention or the scope of the subjoined claim.

Having thus described my invention, I claim:—

In a device of the character described, the combination of an outlet box, lugs formed on the sides of said outlet box, an insulating member having cut-away portions on the periphery thereof, ledges formed on said insulating member, said insulating member being provided with openings therethrough, contacts secured on the exposed face of said insulating member, a cap adapted to overlie said outlet box and said insulating member, a bushing carried by said cap, said bushing being adapted to receive a light fixture, and contacts carried on said cap and adapted to engage said first mentioned contacts. 35 40 45

In testimony whereof I affix my signature.

DONALD A. ROSE.
